(57) **CLAIM**

The ornamental design for a handheld communication device, as shown and described.

DESCRIPTION

FIG. 1 is a front perspective view of an ornamental design for a handheld communication device;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

All broken lines in the figures illustrate portions of the handheld communication device that form no part of the claimed design. The broken lines that are immediately adjacent to shaded areas, and define unshaded regions, depict boundaries of the claimed design.
